NEW YORK

CONVERTIBLE SAFETY RAZOR

Application filed March 5, 1932. Serial No. 596,962.

This invention relates to safety razors and particularly to a construction thereof which permits of the ready conversion of the safety razor into a stropping device whenever desired. With a razor constructed in accordance with the present invention, the replaceable blades thereof may be sharpened as soon as there is any indication of their losing any of their original sharpness, and the life of the blades may accordingly be greatly lengthened and the keeness of their cutting edges can be constantly maintained in a highly satisfactory state.

It is a purpose to form the convertible razor of a comparatively few simple parts that are free from operating mechanism that is likely to get out of order, which parts remain in rigid correlation when in use either as a razor or stropper. The parts are, however, susceptible to a fine adjustment when combined as a razor, whereby the blade and its guard are relatively settable to regulate the fineness of the shaving quality of the razor in accordance with the desire of its user.

Due to the substantial symmetry of the parts and the reasonable restriction of their size, the convertible razor is convenient to use as such or as a stropper, and may be conveniently contained in a compact case or container.

Other features not already specifically mentioned but appearing hereinafter are, of course, to be understood to form part of the present invention.

In the drawing,

Fig. 1 is a perspective view of the tonsorial device assembled as a safety razor;

Fig. 2 is another perspective view, showing the safety razor converted into a stropper;

Fig. 3 is a view partly in section, with the sectional portion being taken on the line 3—3 of Fig. 1, the handle being shown in elevation;

Fig. 4 is a plan view of the tonsorial device assembled as a razor and viewed from the handle end, parts being broken away for improved illustration;

Fig. 5 is an enlarged sectional view taken

on the line 5—5 of Fig. 2, showing the parts assembled either as part of a razor, or as a stropping device; and

Fig. 6 is an exploded view, showing the razor-forming parts in separated vertical alignment, a portion only of the handle being shown.

Referring to the drawing, 1 indicates the curved cheek plate that is applied to the user's cheek in shaving. The cheek plate is provided with a recess or cavity 2 in its normally inner side, which recess is of somewhat less length and width than the extreme longitudinal and transverse dimensions of the cheek plate 1. When the tonsorial device is assembled as a razor it includes a female clamping plate 3 which has a main body portion having a convex side that is inset in the recess of the cheek plate 1. The main body portion of the clamping plate 3, exclusive of its opposite end portions, has a length and width substantially co-extensive with the similar dimensions of the recess 2. In the side of the clamping plate 3 that is opposite to its side that lies against the cheek plate 1 is a rectangular recess 4 adapted to receive a rectangular tongue 5 of a male clamping plate 6. The tongue 5 is approximately of the same length and width as the recess 4 in the clamping plate 3, and the two clamping plates 3 and 6 are, if desired, of the same length and width.

A razor blade 7, which may be thin and flexible, is interposed between the two clamping plates 3 and 6, and is provided with a longitudinally extending slot 8 conforming to the tongue 5 of the clamping plate 6 to permit the blade 7 to be slipped onto this tongue to closely surround the same, whereby the blade is definitely positioned in place. The main body portion of the male clamping plate 6 has spaced intermediate convex portions 6a and 6b that taken together fit into and conform to a rectangular recess 9 in the adjacent concave side of a guard 10, opposite edges of which guard are provided with short prongs or tines with notches therebetween.

Beyond the intermediate convex portions 6a and 6b of the clamping plate 6, the oppo-

site end portions 6c and 6d of the latter are of somewhat less radius than the portions 6a and 6b, and are conformed to the internal concave surfaces of the corresponding ends 5 of the guard member 10. Similarly, the opposite end portions 3c and 3d of the female clamping plate 3 have convex curvatures of somewhat less radii than the intermediate convex portion of clamping plate 3. The 10 end portions 3c and 3d are conformed to the curvature of the opposite end portions of the normal inner side of the cheek plate 1. By virtue of this arrangement, the external ends of the cheek plate 1, clamping plates 3 and 6, the guard 10 and the razor blade 7 are 15 maintained flush with one another.

Extending through centrally located holes in the clamping plates 6 and 3 is a bushing 11 that is provided with an annular head or 20 flange 12 that lies against a flat surface of the clamping plate 6 between the spaced intermediate convex portions 6a and 6b thereof. The opposite end of the bushing 11 is threaded and screwed into the threaded central hole in the clamping plate 3, thereby 25 securely clamping the clamping plates 3 and 6 and the blade 7 interposed therebetween tightly together. The annular head or flange 12 of the bushing 11 is provided with means, 30 such as spaced lugs or ribs 13, by means of which the bushing 11 may be screwed into or out of the clamping plate 3, according to whether a blade 7 is to be clamped in place or to be removed for replacement.

35 A handle 14 is provided with a screw threaded end 15 of reduced diameter, which passes through a central hole in the guard 10 and through the bushing 11 to be screwed into a threaded central hole in the cheek 40 plate 1. A shoulder 16 existing between the main body portion of the handle 14 and its reduced end 15 bears against a boss on the external central portion of the guard 10, so that, when the handle 14 is adjustingly 45 turned, the cheek plate 1, clamping plates 3 and 6 with the blade 7 and the guard 10 are appropriately clamped together. The tonsorial device is then usable as a safety razor, and the blade 7 is subject to regulation with 50 respect to its guard 19 and the cheek plate 1 by a limited turning of the handle 14 to determine the closeness of the shave in accordance with the desire of the user.

After a certain amount of use of the razor, 55 it will be perceived that its blade is not as sharp as it originally was. Thereupon, the user may unscrew the handle 14 from the cheek plate 1 and withdraw its reduced end 15 through the bushing 11 and the clearance hole in the guard 10. The cheek plate 1 and the guard 10 are then removed and set conveniently aside. The remaining 60 nested clamping plates 3 and 6 still firmly held together by the bushing 11, with the 65 razor blade 7 gripped and positioned there-

between, constitute a blade stropping device that is complete and ready for use, except for a handle. The handle 14 is then attached to this stropping device assembly by screwing its reduced threaded end 15 into 70 a threaded hole 17 in a lug 18 that is integral with the end portion 6c of the clamping plate 6 on the side of the latter that lies next to the blade 7. The inner side of the lug 18 is outside of an indented end 19 75 of the razor blade 7, spaced extensions 20 of which embrace parallel sides of the lug 18. This lug projects so that it bears against the curved inner end of the cheek plate 1 to which it is conformed. The end 80 3c of the clamping plate 3 is cut out at 21, whereby it acquires spaced prongs 22 and fits about the lug 18. The prongs 22 are also curved to fit the cheek plate 1. A complete stropping device provided with a removable handle is thus formed, with the razor blade 7 firmly clamped between and reinforced by the clamping plates 3 and 6. The user then reversely draws the razor 85 blade 7 across a strop to sharpen its edges, and at appropriate times turns the stropping device in his hand through a one-half revolution, while the blade is not applied to the strop, so that both sides of each edge of the double-edged razor blade 7 are properly stropped. If desired, an enveloping 90 guard may be slipped over one of the cutting edges of the razor to house it while the other cutting edge is being stropped, and then be transferred to the first sharpened edge. The major convex surfaces of the clamping plates 3 and 6 have such curvature that when either convex surface and the edge of the razor blade simultaneously 95 contact with the strop, an angular relation 100 between the strop and the razor blade edge is predeterminedly established, as indicated by the line α — α of Fig. 5, whereby the edge of the blade is sharpened at a proper angle. When the user has sharpened the edges of 105 the razor blade to the desired degree of keenness, the parts are reassembled to again 110 form the safety razor, which is once more in condition for highly satisfactory service.

While a preferred form of the convertible tonsorial device has been illustrated and described, it may partake of other forms, and changes may be made in its details, without departing from the spirit of the invention as defined by and within the scope 115 of the appended claims.

We claim:

1. A safety razor comprising a cheek plate and a guard member provided with opposing recesses, co-acting blade-holding members combined as a removable unit and being retained between said cheek plate and guard member and entering the recesses thereof, a razor blade interposed between and positioned by said holding members, and a han- 120 125 130

- dle screwed into said cheek plate and bearing against said guard member adjustably clamping said plate, members and blade in mutual correlation.
5. 2. A safety razor comprising a cheek plate and a guard member provided with opposing recesses, blade-clamping members retained between and entering the recesses of said cheek plate and guard member, said 10 clamping members fitting one into the other, a razor blade interposed between said clamping members and positioned thereby, and a handle screwed into said cheek plate and bearing on said guard member adjustably 15 clamping said plate, members and blade in mutual correlation.
3. A convertible safety razor comprising a cheek plate and a guard member provided with opposing recesses, blade-clamping members fitting one into the other and retained between and entering the recesses of said cheek plate and guard member, a razor blade interposed between and positioned by 20 said clamping members one of the latter being provided with handle-attaching means, and a removable handle adjustably combining said cheek plate, members and blade adapted to be removed and combined with 25 said blade-clamping member handle-attaching means, said cheek plate and guard member being removable to convert said razor into a stropping device.
4. A convertible safety razor comprising a cheek plate and a guard member, blade-35 clamping members fitting one into the other and inset respectively in said cheek plate and guard member, a razor blade interposed between and positioned by said clamping members, clamping means for said blade-40 clamping members, one of the latter being provided with handle-attaching means, and a removable handle adjustably attached to said cheek plate and co-acting therewith to clamp said blade-clamping members, said 45 blade and guard member therebetween, said handle, cheek plate and guard member being removable and said handle being attachable to said blade-clamping member handle-attaching means to convert the razor into a 50 stropping device.
5. A convertible safety razor comprising a cheek plate, a guard member, blade-clamping members fitting one into the other and respectively into said cheek plate and guard 55 member, a razor blade between and positioned by said clamping members, clamping means for said blade-clamping members, one of the latter having handle-attaching means, and a handle passable through the members 60 and attachable to said cheek plate, said cheek plate, guard member and handle being removable and the handle being attachable to said blade-clamping member handle-attaching means to convert the razor into a stropping device.
6. A convertible safety razor comprising a cheek plate, a guard member, blade-clamping members fitting one into the other and respectively into said cheek plate and guard 70 member, a razor blade between said clamping members, an adjustable tubular clamping element rigidly combining said clamping members, one of the latter having handle attaching means, and a handle passage through the members and tubular clamping element, and attachable to said cheek plate, 75 said cheek plate, guard member and handle being removable and the handle being attachable to said blade-clamping member handle-attaching means to convert the razor into a stropping device.
7. A convertible safety razor comprising a cheek plate, a guard member, blade-clamping members retained between said cheek plate and guard member, a razor blade retained between said clamping members, the latter being provided with handle attaching means, clamping means for said blade-80 clamping members, and a handle combining said cheek plate and the members, said cheek plate, guard member and handle being removable and the handle being attachable to said handle-attaching means of the clamping members to form a stropping device, the 85 clamping members being formed to determine the cutting edge of the blade.
8. A convertible razor comprising removable exterior members forming a socket, blade-clamping members, normally in said socket, a blade retained between said clamping members, one of said clamping members having an end provided with a recess, another of said clamping members having a lug at one end fitting into said recess, 90 said lug being provided with handle-attaching means, adjustable means clamping said clamping members and blade together, and a removable handle selectively attachable to certain of said exterior members to form a 95 razor and to the handle-attaching means of said lug to convert said razor into a stropping device when certain of said exterior members have been removed.
9. A convertible tonsorial device comprising separable blade-holding members normally in unitary combination and provided with handle-attaching means, a removable razor blade held by said members, exterior members formed to receive the combined blade-holding members and for facial contact, and a handle selectively attachable to 100 said exterior members and to said handle-attaching means of said combined blade-holding means, said exterior members being removable from said combined blade holding members.
10. A convertible tonsorial device comprising separable blade-clamping members and a removable razor blade combined as a unit,

said unit being provided with handle-attachment means, removable exterior members forming a socket for said unit, and a handle-forming element adapted to clamp said members together and to be attached to said handle-attachment means upon the removal of said exterior members.

11. A convertible tonsorial device comprising a blade-holder formed as a stropping unit 10 provided with handle-attachment means, a razor blade retained by said unit, members adapted for facial contact exterior to said unit, and a handle combined with said members and unit and adapted to be applied to 15 said handle-attachment means, said exterior members being removable.

12. A convertible tonsorial device comprising a blade-holder formed as a stroping element provided with handle-attachment 20 means, exterior members socketed to receive said blade-holder, a razor blade retained by said holder, and clamping means including a holding-handle combining said members and blade-holder and being adjustable to 25 vary the relation of the razor and member edges to affect cutting by said blade, said exterior members being removable and said handle being adapted to be applied to said handle-attachment means.

30 13. A convertible tonsorial device comprising a razor blade, members on opposite sides thereof forming a holder therefor, said holder being provided with handle-attachment means, separate outer removable plate-like 35 members respectively disposed on opposite sides of said holder and having edges controllingly related to the razor blade edges, and a holding-handle adjustably clamping said members together and being removable 40 to permit the removal of said outer members and for its own attachment to the handle-attachment means of said holder.

14. A convertible tonsorial device comprising a blade-holder formed of mutually combined nested members and provided with handle-attachment means, a razor blade held between said members, separately formed external members in which said holder is nested, one of said members being a 50 razor blade edge guard, and a holding-handle combining said members, said handle being removable to permit the removal of said external members and for its own attachment 55 to the handle-attachment means of said holder.

15. A convertible tonsorial device comprising a plurality of inner and outer plate-like members, successive members being formed 60 to fit one into the other, a razor blade held by said inner members, means for maintaining said inner members co-operatively engaged, the outer members being removable at will to convert said inner members into a 65 stropping device and a handle selectively at-

tachable at different angles to the members selected for use.

In testimony whereof, we have affixed our signatures.
